Patented Feb. 13, 1968

210,161

TAPE COILER

Irving Allen, Hamden, Conn., assignor to Connecticut Scientific Center, Inc., New Haven, Conn., a corporation of Delaware

Filed Jan. 13, 1967, Ser. No. 5,462

Term of patent 14 years

(Cl. D52—1)

Fig. 1.

Fig. 2.

Fig. 3.

FIG. 4.FIG. 5.FIG. 6.FIG. 1 is a top plan view of a tape coiler showing my new design;

FIG. 2 is a front elevational view;

FIG. 3 is a bottom plan view;

FIG. 4 is a front elevational view showing the tape coiler in another position to that of FIG. 2;

FIG. 5 is a top plan view of an alternate embodiment of the tape coiler according to my design; and

FIG. 6 is a side elevational view of the alternate embodiment of FIG. 5.

I claim:

The ornamental design for a tape coiler, as shown and described.
